UNITED STATES PATENT OFFICE.

CHARLES E. POWELL, OF PHILADELPHIA, PENNSYLVANIA.

RAILWAY-RAIL AND JOINT.

No. 836,462.

Specification of Letters Patent.

Patented Nov. 20, 1906.

Application filed September 6, 1906. Serial No. 333,464.

To all whom it may concern:

Be it known that I, CHARLES E. POWELL, a citizen of the United States, residing at Philadelphia, county of Philadelphia, and State of Pennsylvania, have invented a certain new and useful Improvement in Railway-Rails and Joints, of which the following is a specification.

My invention relates to a new and useful improvement in railway-rails and joints, and has for its object to provide exceedingly simple and effective devices of this description which will absolutely prevent the meeting ends of the rails from moving out of line and which will also prevent the rails from spreading by side pressure from the train.

With these ends in view this invention consists in the details of construction and combination of elements hereinafter set forth and then specifically designated by the claims.

In order that those skilled in the art to which this invention appertains may understand how to make and use the same, I will describe its construction in detail, referring by letter to the accompanying drawings, forming a part of this specification, in which—

Figure 1 is a perspective of the meeting ends of two rails; Fig. 2, a section through one of the rails, showing fish-plates in place thereon; Fig. 3, a side elevation of a clamp-spike for holding the rails to the ties; Fig. 4, an edge view thereof; and Fig. 5, a side elevation of a spike adapted for use where extra side strains are developed, such as upon curves.

In carrying out my invention as here embodied, A and A' represent the opposite ends of two rails, each rail having the flanges B formed therewith, said flanges being provided with the holes C for the passage of the spikes, as hereinafter set forth.

At the end A of each rail the flanges B project beyond the web and head of the rail, thus forming the socket D, while at end A' of each rail the flanges B are cut away, so that the tread-web and head of the rail project beyond the flanges B in such manner as to be adapted to pass within the socket D, and thus be held against any sidewise displacement.

When a track is laid with these rails, it is obvious that the ends thereof cannot get out

of alinement with each other, and in order to further prevent the possibility of the rails being displaced independent of each other I 55 so construct the fish-plates E that they will fit snugly against the web beneath the head of the rail and upon the base and against the inner surfaces of the flanges B, thus securely tying the rails together at each joint. 60

The flanges B are utilized for securely holding the rails to the ties by means of the spikes F, the body of each of which is intended to be driven into the tie, while the nose G thereof is intended to fit over the edge of the flange B, while the heel H is also partially driven into the tie and serves as a support to prevent the bending of the spike backward away from the rail, and as the body of the spike is driven directly against the flange B 70 very much greater resistance is offered to the spreading of the rail than would be by the use of the ordinary spike.

At points where the side thrust of the train upon the rails increases the tendency to 75 spread the rails I prefer to use the spikes I, which consist of a body adapted to be driven into the tie and a nose K, adapted to be driven through the flange B and into the holes C and thence downward into the tie, 80 while the heel K of this spike is also partially driven into the tie, so as to prevent the backward bending of the spike. By the use of this spike on curves or at other points where the tendency to spread the rails is unusually 85 great three holds are had upon the tie, and any spreading will be rendered impossible.

Rails and joints made in accordance with my improvement entirely overcome the disadvantage heretofore experienced in railroad 90 construction and operation, in that the ends of the rails cannot get out of alinement with each other, and therefore cannot be worn away by the snubbing off of these ends, as has heretofore been the case, thus increasing 95 the life of the rail and also preventing the numerous accidents which are of constant occurrence on account of the spreading of the rails.

Having thus fully described my invention, what I claim as new and useful is—

1. In combination, a railway-rail having flanges formed upon the base thereof, said flanges projecting beyond one end of the rail

and cut away at the other end, fish-plates adapted to fit against the web beneath the head of the rails and upon the base and against the inner surface of the flanges, as and for the purpose set forth.

2. In combination with a railway-rail of the character described, a spike having a body adapted to be driven into the tie, a nose adapted to fit through the flanges of the rail,

and a heel adapted to back up the spike, as specified.

In testimony whereof I have hereunto affixed my signature in the presence of two subscribing witnesses.

CHARLES E. POWELL.
